TOY SPINNING TOP

Herbert A. Plassmann, Bryan, Ohio, assignor to The Ohio Art Company, Bryan, Ohio

Filed Aug. 20, 1971, Ser. No. 173,712

Term of patent 14 years

Int. Cl. D21—01
U.S. Cl. D34—15 CC

The figure shown is a perspective view of a toy spinning top showing my new design; the undisclosed opposite side being substantially the same.

I claim:

The ornamental design for a toy spinning top, substantially as shown and described.
